[57] CLAIM

The ornamental design for a compact for cosmetics, substantially as shown and described.

DESCRIPTION

FIG. 1 is a front perspective view of a compact for cosmetics showing my new design;
 FIG. 2 is a side elevational view, the opposite side being a mirror image thereof;
 FIG. 3 is a top plan view thereof;
 FIG. 4 is a front elevational view thereof;
 FIG. 5 is a rear elevational view thereof;
 FIG. 6 is a front perspective view in opened position;
 FIG. 7 is a front perspective view of a modified version thereof; and
 FIG. 8 is a front perspective view of the compact of FIG. 7 in opened position.
